(57) **CLAIM**

The ornamental design for an exterior surface configuration of an air compressor cover, as shown and described.

DESCRIPTION

FIG. 1 is a perspective view of the exterior surface configuration of an air compressor cover, looking down at the top and right side thereof, the other components of a power operated air compressor assembly in which the cover is embodied being shown in phantom lines;

FIG. 2 is an another perspective view looking down on the top and left side thereof without the phantom line showing; FIG. 3 is a front elevational view thereof;

FIG. 4 is a left side elevational view thereof, the right side elevational view being a mirror image thereof;

FIG. 5 is a top plan view thereof; and,

FIG. 6 is a bottom plan view thereof.

It being understood that the broken lines are for illustrative purposes only.
